UNITED STATES PATENT OFFICE.

FRANZ FR. BÜRGER, OF MANNHEIM, GERMANY, ASSIGNOR, BY MESNE ASSIGNMENTS,
TO HEINRICH LANZ, AKTIENGESELLSCHAFT, OF MANNHEIM, BADEN, GERMANY,
A CORPORATION OF GERMANY.

STEAM SUPERHEATER.

Application filed November 4, 1924, Serial No. 747,721, and in Germany January 30, 1924.

This invention relates to a superheater, and, more particularly, to that type of superheater in which two semi-circular coils are housed in an annular chamber usually, 5 in the case of locomobile, locomotive and similar boilers, within the smoke-box.

It is a well-known practice to locate a superheater in the smoke-box of a locomobile or locomotive boiler and to direct the 10 flue gases from the boiler through the superheater, through a front inlet opening at the top and a rear outlet opening at the bottom of the superheater chamber, by closing a centrally mounted damper. As heretofore 15 constructed, however, it has been impossible to provide any means for closing the inlet and outlet openings of the superheater chamber.

The object of my present invention is to 20 obviate this defect; and this end I have attained in my new superheater by providing control means whereby the combustion gases may be positively directed from or to the 25 boiler either wholly through or wholly without, or in part through and in part without, the superheater chamber as desired.

The invention will be understood by reference to the accompanying drawing where- 30 in is shown, in Fig. 1 in vertical longitudinal section and in Fig. 2 in transverse section, a smoke-box superheater embodying my improvement.

Referring to the drawing, 1 indicates the 35 end of a fire-tube boiler, and 2 the smoke-box adjacent thereto. The cylindrical wall or casing of the smoke-box is attached at its inner end to the boiler and to its outer end is fixed the end plate 5 which is fitted 40 with a door 5¹, removably secured thereto by the usual turn-buckles or the like, having formed therein a centrally located passage 4 for the exhaust gases. Within the smoke- 45 box, the superheater 3, comprising two semi-circularly disposed coils, is mounted on the smoke-box walls in the annular chamber which is formed by these walls and an inner cylindrical wall 6, carrying midway its length a transverse wall 7, rigidly attached 50 to the inner face of and removable with the door 5¹. The transverse wall has a centrally located opening 8, in alignment with the exhaust passage 4, which is opened and closed by the damper 9 mounted therein

and controlled from outside the casing. The 55 cylindrical wall 6 is provided at the top, on the boiler side of the transverse wall, with the opening 11 which is controlled, from without, by the two dampers 11¹ and 11² mounted therein and which serves as the 60 inlet opening to the superheater chamber and at the bottom on the exhaust side of the transverse wall with a corresponding outlet opening 10 which in like manner is controlled by the similarly mounted dampers 65 10¹ and 10².

Thus, when the dampers 10¹ 10² and 11¹ 11² are open and the damper 9 is closed all the flue gases from the boiler will pass through the superheater on their way 70 to the exhaust. If, on the other hand, the positions of these dampers are reversed so as to close the openings 10 and 11, and open the opening 8, the flue gases will flow directly from the boiler to and out through 75 the exhaust. And by suitably manipulating the dampers a greater or lesser part of the flue gases, as desired, can be directed through the superheater while the remaining part passes directly to the exhaust. 80

Furthermore, when the door of the smoke-box is unfastened and removed the inner cylindrical wall and the dampers mounted thereon will be withdrawn with it, thus opening up the entire superheater for 85 the purpose of cleaning, adjustment, or repairs.

It is evident that my improved superheater may also be used, without substantial change, in connection with boilers of 90 the type in which it is desirable to so locate the superheater that the combustion gases can be passed through it before passing through the boiler.

What I claim as new, and desire to secure 95 by Letters Patent, is—

1. A steam-superheater of the type described comprising, in combination with a casing provided with inlet and outlet openings for the passage of combustion gases 100 and with two semi-circular banks of superheater coils mounted therein, an inner wall which extends from end to end of the casing within the superheater coils and divides the interior of the casing into an outer superheater chamber and an inner central passage, openings in the inner wall which are located at or adjacent one end in its upper 105

side and at the other end in its lower side between the two banks of coils, and dampers controllable from outside the casing which are adapted to open and close said openings 5 in the inner wall and the passage therethrough between the openings, whereby the combustion gases may be directed from the inlet to the outlet opening of the casing wholly or in part either directly or through 10 the superheater chamber.

2. A steam superheater of the type described comprising, in combination with a casing provided with inlet and outlet openings for the passage of combustion gases 15 and with two circularly disposed banks of superheater coils mounted therein, a cylindrical wall forming a longitudinal annular passage, provided with openings located at or adjacent one end in one of its sides and 20 at the other end in its opposite side and carrying dampers operable to open and close the said openings therein and the passage therethrough between the openings, which is adapted to be inserted into and withdrawn 25 from the casing and which when in place therein extends from end to end thereof within the superheater coils and provides inner direct and surrounding outer indirect damper-controlled passages from the inlet 30 to the outlet opening of the casing.

3. A steam superheater of the type described comprising, in combination with a cylindrical casing provided with inlet and outlet openings in its opposite ends and having 35 two semi-circular banks of superheater coils mounted therein, an inner cylindrical wall which is adapted to be inserted into and to be withdrawn from the casing and when in place therein divides the interior thereof into an outer annular superheater chamber and a central passage in communication at one end with the inlet opening and at the other end with the outlet opening of 40 the casing, which is provided with openings located at one end in its upper side and at the other end in its lower side between the two banks of coils, and which carries dampers mounted thereon and operable to open and close the said openings therein and the 45 central passage intermediate said openings, whereby the combustion gases may be directed from the inlet to the outlet opening of the casing wholly or in part either directly through the central passage or through 50 the two banks of coils in the surrounding superheater chamber.

4. A superheater of the type described, comprising a casing with outer and inner cylindrical walls forming an annular chamber closed at both ends and a central passage open at one end for the admission and at the other end for the discharge of the combustion gases, a superheater coil mounted within the annular chamber, a transverse wall 60 within the inner tubular wall approximately 65

midway the length thereof having a centrally located opening, means controllable from outside the casing for opening and closing said central opening, an opening through the top of the inner cylindrical wall on the 70 inlet side of the transverse wall, a second opening through the bottom of the inner cylindrical wall on the outlet side of the transverse wall, and means controllable from outside the casing for opening and closing one at least of said top and bottom openings.

5. A superheater of the type described, comprising a cylindrical casing with end walls each of which has a circular opening therein, a circular door-plate provided with central opening which fits the opening in one of the end walls of the casing, means for removably securing the door-plate in place within the said end wall opening, an inner cylindrical wall which is rigidly secured to the inner face of and is removable with the door-plate and which when the door-plate is in position extends the length of the casing and at its free end abuts the other end wall thereof, superheater coils which are mounted on the casing within the annular chamber formed by its walls and the inner cylindrical wall, a transverse wall which is carried within the inner cylindrical wall substantially midway of its length and has a centrally located opening therein, means controllable from outside the casing and removable with the wall for opening and closing the said opening therein, openings which are formed in the inner cylindrical wall at one end in the upper side and at the other end in its lower side, and means controllable from outside the casing and removable with the wall for opening and closing at least one of the said openings therein.

6. A steam superheater comprising, in combination, a cylindrical casing adapted to be attached at its inner end to the end of a boiler in communication with the gas-circulating system thereof and having in its outer head an opening for the passage of furnace gases, an inner concentric cylindrical wall which divides the interior of the casing into an inner central passage surrounding the opening to the boiler and connecting the same with the said outer opening and an outer annular chamber, two semi-circular banks of superheater coils mounted within the outer annular chamber one on each side thereof, and means controllable from outside the casing for closing or partially closing the said central passage intermediate its ends and for opening communication between the central passage and the annular chamber on the upper side at one end and on the lower side at the other end thereof.
